(57) **CLAIM**

The ornamental design for a tread portion of an automobile tire, as shown and described.

DESCRIPTION

FIG. 1 is a front view of a tread portion of an automobile tire;
FIG. 2 is a perspective view thereof;
FIG. 3 is a left side view thereof;
FIG. 4 is a right side view thereof;
FIG. 5 is a fragmentary enlarged view showing the details thereof;

FIG. 6 is an end view taken along line 6-6 in FIG. 5; and,
FIG. 7 is an end view taken along line 7-7 in FIG. 5.
In the drawings, the broken lines defining the unclaimed tread
region, sidewall, and the inner bead of the tire depict environmental
subject matter that forms no part of the claimed
design.
